United States Patent Office

Des. 201,155
Patented May 18, 1965

201,155

PIANO

Wilbur M. Day, Kenwood, Ohio, assignor to D. H. Baldwin Company, Cincinnati, Ohio, a corporation of Ohio

Filed Oct. 3, 1963, Ser. No. 76,848

Term of patent 14 years

(Cl. D56—9)

The figure is a perspective view of a piano embodying my new design.

The dominant features of the design reside in the portions shown in full lines.

I claim:

The ornamental design for a piano, substantially as shown and described.
